UNITED STATES PATENT OFFICE.

HENRY H. CUMMINGS, OF MALDEN, MASSACHUSETTS, ASSIGNOR, BY MESNE ASSIGNMENTS, TO UNION LOCK STITCH COMPANY, OF BOSTON, MASSACHUSETTS, A CORPORATION OF MAINE.

LOCK-STITCH SEWING-MACHINE.

964,852.

Specification of Letters Patent. Patented July 19, 1910.

Application filed September 25, 1903. Serial No. 174,638.

To all whom it may concern:

Be it known that I, HENRY H. CUMMINGS, a citizen of the United States, residing at Malden, in the county of Middlesex, State 5 of Massachusetts, have invented a certain new and useful Improvement in Lock-Stitch Sewing-Machines, of which the following is a specification, reference being had therein to the accompanying drawings.

10 Figure 1 of the drawings is a view showing in front elevation portion of a sewing machine having an embodiment of the invention applied thereto, a part of the fixed casing of the machine being represented in 15 vertical section. Fig. 2 is a view of the same parts looking from the left hand side in Fig. 1, showing a part of the said casing in vertical transverse section. Fig. 3 is a view in plan of portion of the same, with the 20 work support omitted.

Having reference to the drawings,—a part of the base of the fixed casing of the sewing machine is shown at 1, and at 2 is 25 shown a post or standard which is secured upon the said base and extending upward therefrom. 3 is a work-rest or work-support upon the upper end of the said post or standard 2. 4 is an ordinary hooked needle, and 41 the needle-bar carrying the same. 30 The said needle-bar is held in guides 42, 42, and actuated through suitable connections, which latter herein are constituted by the link 43, the crank-pin 44, the disk 45 carrying the said crank-pin, and the shaft 46 on 35 which the said disk is mounted. At 5 is shown a rotary loop-taker, herein a shuttle, containing a bobbin as usual. At 7 is the shuttle-driver by means of which the said shuttle is rotated. The said shuttle-driver 40 is fixed upon the upper end of the upright shaft 71, which latter is driven by means of the bevel pinion 72 upon its lower end meshing with the bevel gear 73 fast upon the horizontal rotating shaft 46. As thus far 45 referred to, the various parts are or may be as heretofore or as preferred, save as I will hereinafter indicate in treating of the features in which my invention more especially resides.

50 In conformity with one portion of my invention, I provide a finger, which is movably mounted adjacent to the path of the needle and that of the nose of the loop-taker or shuttle, and is provided with actuating connections whereby, as the needle draws a loop

of needle-thread through the work, the said finger is caused to move synchronously with the needle but at a different rate of speed and to operate, while the drawing movement of the needle continues, to take the loop out 60 from under the hook of the needle by a movement in the same direction with that of the needle but faster than the latter, thereby disengaging the loop from the moving needle. The finger holds the loop while 65 the needle completes its movement away from the work, and also serves as a restrainer by means of which one side of the loop is held against the tendency of the rotating loop-taker or shuttle to carry the 70 loop around with it in its rotation. The said finger, in other words, operates to disengage the loop from the needle while the latter is continuing its withdrawing movement, and also as a loop-restrainer to prevent 75 one side of the loop from being carried around within the shuttle-race by the shuttle in its rotation. Herein, the finger in question is shown at 8.

The means of supporting and actuating 80 the finger may vary in practice. Herein, it is mounted upon a rod 9 that is mounted to turn in a bearing or bearings with which the post or standard 2 is provided. For the purpose of communicating movement to 85 the rod and finger, the said rod 9 is shown provided, at the end thereof opposite that to which the finger is applied, with a crank-arm 91, which latter is connected by means of a rod 92 with an arm or lever 93, the said 90 arm or lever being mounted pivotally upon a screw 94 which is applied to the base 1, and being provided with a roll 95 against which acts a cam 96 which is fast upon the rotating shaft 46. By means of the said 95 cam and arm or lever, and the connections from the last mentioned part to the rod 9 upon which the finger 8 is mounted, the said finger is oscillated in a vertical plane. The cam is shaped and proportioned to cause the finger to operate as aforesaid. The free end of the finger is pointed, so as to facilitate the entrance of the said end between the opposite sides of the loop which is being drawn down by the needle. The finger is 100 slotted as at 81 to receive the upper end of the needle as the finger swings downward. The pointed end of the finger enters the loop above the end of the needle, and the 105 downward swing of the finger is so speeded 110

as to cause the operative end of the same to gain upon the needle as the latter descends. The finger in being depressed acts by reason of the said gain to disengage the loop from under the hook of the needle, and then operates to carry the loop laterally away from the said hook in consequence of the divergence of the curved path of the working end of the finger from the path of movement of the needle. The finger remains in its depressed position, holding the loop, which it has disengaged from the needle, while the needle continues its descent. Meantime, the tip of the loop-taker or shuttle enters the loop. The finger operates to restrain one side of the loop so as to prevent the entire loop from being carried around within the shuttle-race by the shuttle in its rotation.

20 One portion of my invention consists in an improved construction of the shuttle-race which facilitates the operation of inserting and removing a shuttle. The shuttle-race is composed of thin plates 10, 10, and 101, occupying a horizontal position and shaped to surround the shuttle. The shuttle is formed with a circumferential groove 51 into which the edges of the said plates fit. For the purpose of providing for the convenient insertion and removal of the shuttle, the intermediate plate 101 is removably applied to the side plates 10, 10, it being fitted at its ends to slide in guides or ways with which the latter plates are provided, 102 being a notch in the outer portion of the plate 101 which is intended to receive the thumb-nail of the operator, or the end of a suitable tool, for the purpose of facilitating the removal of the said plate.

40 As will be apparent from the drawings and foregoing description, the needle and loop-taker or shuttle are both located at the same side of the material which is to be stitched, and, also, the loop-taker or shuttle rotates in a plane at right angles to the plane containing the path of movement of the needle. The body of the shuttle, and the shuttle-race, are located at a slight distance laterally from the line of movement of the needle and needle-bar. In order that the loop of thread which is drawn by the needle may become properly engaged by the shuttle without requiring the aid of a moving device to engage the side of the needle-loop and carry it over to the loop-taker or shuttle, the latter is provided with a tip or loop-taking point 52 which projects radially beyond other portions of the shuttle-body and of the shuttle-race, so as to nearly or substantially intersect the path of movement of the needle. The said tip or point constitutes, in effect, a projecting picking device, forming part of the loop-taker or shuttle, and taking the place of the separate movable loop-opener which in other constructions of

sewing machines is employed for the purpose of presenting one side of the needle loop within the path of movement of the usual shuttle-tip.

I claim as my invention:—

1. In a sewing machine, in combination, a hooked needle operating to draw a loop of needle-thread through the material which is to be stitched, a loop-taker, a finger, and operating means for the said finger acting to cause it to disengage the said loop from the moving needle by movement communicated to the said loop in the same general direction with that of the needle but faster than the latter, and to hold one side of the loop against the tendency of the loop to carry the loop therewith. 70

2. In a sewing machine, in combination, a hooked needle operating to draw a loop of needle-thread, a shuttle-race, a shuttle, a finger, and operating means for the said finger acting to cause it to disengage the loop from the needle by movement communicated to the said loop in the same general direction with that of the needle but faster than that of the needle, and to hold one side of the loop against the tendency of the shuttle to carry the loop into the shuttle-race. 85

3. In a sewing machine, in combination, a hooked needle, a loop-taker, a finger moving in proximity to the paths of the needle and of the tip of the loop-taker, having a pointed free end to enter the needle-loop and slotted for the passage of the needle therethrough, and means for operating the said finger to cause it to enter the needle-loop and disengage the said loop from the needle by movement communicated to the loop in the same general direction with that of the needle, but faster than that of the needle. 95

4. The combination with the hooked needle and reciprocating needle-bar, of the rotating shuttle operating at the same side of the work as the needle-bar and needle, the said shuttle rotating in a plane at an angle to that of the line of movement of the needle, and having a loop-picking point projecting radially beyond other portions of the shuttle and moving in a path intersecting or substantially so the path of movement of the needle, the said point entering the unopened needle-loop and opening the same for its own complete entrance into such loop. 110

5. The combination with the hooked needle and reciprocating needle-bar, of the loop-taker operating at the same side of the work as the said needle-bar and needle, and also rotating in a transverse plane at an angle to that of the line of movement of the needle, and provided with a radially-projecting loop-picking point which moves in a path intersecting or substantially so the 120

path of movement of the needle and enters the unopened needle-loop, opening the same for its own complete entrance into such loop, and a loop-detent which enters the needle-loop after the latter has been spread by the said loop-taking point of the loop-taker.

6. The combination with the upright post or standard 2, the needle-bar and needle working vertically at one side of the said post or standard, and the shuttle-driver rotating on an upright axis, of the rotary shuttle having the circumferential groove, and the horizontal shuttle-race fitting within the said groove and having the laterally movable section at the side opposite the needle-bar and needle whereby the insertion and removal of the shuttle are permitted.

7. The combination with the upright post or standard, the needle and needle-bar working at one side thereof, and the shuttle-driver rotating on a vertical axis, of the shuttle, and the horizontal shuttle-race having fixed opposite side portions and the removable intermediate portion at the side opposite the needle-bar and needle and fitted to the said side portions.

8. The combination with the hooked

needle and the reciprocating needle-bar, of the loop-taker operating at the same side of the work as the needle-bar and needle, rotating in a plane at an angle to that of the line of movement of the needle-bar and needle, and provided with a loop-picking point which projects radially beyond other portions of the loop-taker and moves in a path intersecting or substantially so the path of movement of the needle, the said point entering the unopened needle-loop and opening the same for its own complete entrance into such loop, and means for producing a plurality of rotations of the said loop-taker to each reciprocation of the needle-bar and needle, the needle occupying a retracted position clear of the path of movement of the said loop-taking point at the time of the intermediate revolution of the loop taker.

In testimony whereof I affix my signature in presence of two witnesses.
